DESCRIPTION

U.S. PATENT DOCUMENTS

FIG. 1 is a perspective view of the telescoping snow brush with scraper, ice chisel and squeegee of the instant invention;

FIG. 2 is a right side view thereof;

FIG. 3 is a left side view thereof;

FIG. 4 is a top plan view thereof;

FIG. 5 is a bottom plan view thereof;

FIG. 6 is a front view thereof; and,

FIG. 7 is a back view thereof.
